UNITED STATES PATENT OFFICE.

TOM HALL, OF FORT SCOTT, KANSAS.

SAFETY SWITCH LOCK.

Application filed June 18, 1925. Serial No. 38,013.

This invention relates to a novel, yet simple device for locking the switch point of a standard railroad switch which is operated by hand so that the switch point will be prevented from moving away from the rails.

One of the important objects of the present invention is to provide a safety switch lock of the above mentioned character 10 wherein the switch point engaging member may be readily and easily bowed to an operative or inoperative position.

A further object is to provide a safety switch lock of the above mentioned character 15 which is of such construction as to permit the installation thereof without necessitating any alterations with respect to the switch or rails.

A still further object is to provide a safety switch lock of the above mentioned character which is simple in construction, inexpensive, strong and durable and further well adapted to the purpose for which it is designed.

Other objects and advantages of the invention will become apparent during the course of the following description taken in connection with the accompanying drawing.

In the accompanying drawing forming a part of this application and in which like numerals designate like parts throughout the same:

Figure 1 is a top plan view of the switch lock embodying my invention showing the manner in which the same is associated with the switch point, the locking lever being shown in its operative position.

Figure 2 is a top plan view of the switch lock per se, and

Figure 3 is a side elevation thereof.

In the drawing, wherein for the purpose of illustration is shown the preferred embodiment of my invention, the numeral 1 designates a standard stationary main rail, the same being secured on the ties 2 in the usual manner. The movable switch point 3 is adapted to be moved into and out of engagement with the stationary rail 1 by any well known type of hand operated standard railroad switches. As the operating means for actuating the switch point forms no important part of the present invention, a further detailed description thereof is not thought necessary.

Oftentimes the switch stand is accident-

tally struck or otherwise disrupted, and as a result, the switch point is thrown out of engagement with the rail and is left in such position, and as a result will cause an on- 60 coming train to be wrecked. For the purpose of locking the switch point against the stationary rail so that there will be no possibility of the switch point being thrown out of engagement with the rail should an accident occur to the switch stand, I have provided a novel switch lock, the construction of which will be presently described.

The switch lock comprises the base plate 4 which is secured on top of one or more of the ties 2 adjacent the switch point, the base plate 4 underlying the stationary rail and the switch point and having one end thereof extending beyond the base flange of the stationary rail on the outermost side 75 thereof. A rail brace 5 is secured on the outer end of the base plate 4, and is adapted to engage the web of the stationary rail 1 in the manner more clearly illustrated in Figure 3.

A pair of spaced upstanding lugs 6 and 7 respectively are secured on the inner end of the base plate 4, the securing means being illustrated at 8. These lugs are provided with registering openings, and also adapted 85 for registry with the aforementioned openings is an opening formed in the inner end of the locking lever 9, the latter being in the form of a flat bar and being twisted adjacent its inner end as at 10 so that the inner 90 end portion thereof is disposed vertically and is furthermore adapted to be interposed between the spaced lugs, and when all of the openings are in registration, a bolt 11 extends therethrough and provides a means 95 whereby the inner end of the locking lever 9 will be pivotally supported between the spaced lugs, so that the locking lever will be adapted for swinging movement in a vertical plane.

The outermost side of the web of the switch point 3 has formed thereon the projection 12, and the purpose will also be presently set forth.

In order to hold the switch point 3 in 105 locked engagement with the adjacent rail 1, after the hand operated switch has been actuated to move the switch point into engagement with the rail 1, the locking lever 9 is swung on its pivot 11 downwardly above 110 the base plate 4 so that the free end of the locking lever will be brought into abutting

relation with the lug 12 formed on the web of the switch point 3 so that when the parts are arranged as shown in Figure 3 of the drawing, the switch point will be locked in its closed position against the rail 1 and should anything happen to the standing switch when the switch point is in the position above described, there will be no danger of the switch point being moved to its open position, thereby preventing any serious accident.

In order that the switch point may be thrown to an open position, the locking lever 9 must be first swung outwardly out of engagement with the lug 12 into the position shown in dotted lines, and when in this position, the switch point may then be thrown out in the usual manner.

It will thus be seen from the foregoing description, that a safety switch lock has been provided which may be readily and easily installed for use in connection with switches of the hand operated type, and the present device will at all times be positive and efficient in carrying out the purposes for which the same is designed.

While I have shown the preferred embodiment of my invention it is to be understood that minor changes in the size, shape and arrangement of parts may be resorted to without departing from the spirit of the invention and the scope of the appended claims.

Having thus described the invention, what I claim as new and desire to secure by Letters Patent is:—

1. In combination with a stationary main rail, a movable switch point including a base flange, a web portion and a head portion,

the base flange of said switch point being adapted to rest on the adjacent base flange of said stationary main rail, a base plate underlying said rail and said switch point, a pair of spaced lugs secured on the inner end of said base plate, a locking lever pivotally supported at its inner end between said lugs, a projection formed on the outer side of the web portion of the movable switch point, the outer free end of said locking lever being adapted to be swung into engagement with said projection on the web portion on the switch point for holding the latter against the stationary main rail.

2. In combination with a stationary main rail, a movable switch point including a base flange, a web portion and a head portion, the base flange of said switch point being adapted to rest on the adjacent base flange of said stationary main rail, a base plate underlying said rail and said switch point, a pair of spaced lugs secured on the inner end of said base plate, a locking lever pivotally supported at its inner end between said lugs, a projection formed on the outer side of the web portion of the movable switch point, the outer free end of said locking lever being adapted to be swung into engagement with the projection on the web portion on the switch point for holding the latter against the stationary main rail, and a rail brace secured on the outer end of the base plate and adapted to engage the outer side of the web portion of the stationary main rail.

In testimony whereof I affix my signature.

TOM HALL.
